UNITED STATES PATENT OFFICE

94,001

DESIGN FOR A PERFUME CONTAINER OR SIMILAR ARTICLE

Joseph S. Stein, Highland Park, Ill., assignor to Lucien Lelong, Inc., Chicago, Ill., a corporation of Illinois

Application September 17, 1934, Serial No. 53,308

Term of patent 7 years

To all whom it may concern:

Be it known that I, JOSEPH S. STEIN, a citizen of the United States, and a resident of the city of Highland Park, county of Lake, and State of Illinois, have invented a new, original, and ornamental Design for a Perfume Container or Similar Article, of which the following is a specification, reference being had to the accompanying drawing, forming a part thereof.

On the drawing:

I claim:

The ornamental design for a perfume container or a similar article, as shown.

JOSEPH S. STEIN.
